UNITED STATES PATENT OFFICE.

NICOLAI B. JOHNSON, OF CHICAGO, ILLINOIS.

ATHLETIC SHOE.

1,229,278.

Specification of Letters Patent. Patented June 12, 1917.

Application filed February 5, 1916. Serial No. 76,252.

To all whom it may concern:

Be it known that I, NICOLAI B. JOHNSON, a citizen of the United States, residing at Chicago, in the county of Cook and State of Illinois, have invented certain new and useful Improvements in Athletic Shoes, of which the following is a specification.

This invention relates to treads on athletic shoes, and particularly to treads to be placed on foot-ball shoes.

One of the purposes of the invention is to provide means for stiffening the sole of the shoe, so that the cleats ordinarily worn thereon will not press through the sole and injure the foot, particularly in wet weather when the soles ordinarily become soft.

A further object of the invention is to provide means whereby the treads may be quickly and conveniently changed, so as to adapt the shoe to the particular weather or other conditions that may exist from time to time.

A further object of the invention is to provide treads to which mud or other wet substances will not cling and to provide cleats of material which is much more suitable than the ordinary leather cleats in common use; and also to fasten the cleats in such a manner as to avoid the disadvantages of the ordinary manner of fastening cleats.

Other objects of the invention will appear upon a consideration of the accompanying drawings, and the description of my invention herein.

Of the accompanying drawings, Figure 1 is a perspective view of sole and heel treads of a shoe which embody features of my invention. Fig. 2, is an enlarged sectional view of one of the cleats showing the means for fastening the cleat to the cleat support. Fig. 3 is an enlarged sectional view of modified means for fastening the cleats; and Fig. 4 is a perspective view of a modified form of tread which may be substituted for the tread shown in Fig. 1 if the weather conditions make it desirable.

As suggested hereinabove, it is desirable to stiffen the sole of the shoe. When the ordinary foot-ball shoe has been worn for some time, even in dry weather, especially if the ground is hard as when frozen, the inner surface of the sole, due to the cleats, becomes uneven, and blisters or calluses are formed on the foot; and this is not only painful and dangerous, but it also reduces the speed of the player; and when the shoe is to be used

in moist weather, the sole softens and these disadvantages are increased. For these and other reasons, I have provided the metal plate 5 to stiffen the sole of the shoe. This plate is substantially of the same form as the sole of the shoe; but, in view of the fact that it is necessary to avoid any liability of the metal pieces on the shoe striking any of the players in the game, I provide plates which are somewhat smaller than the sole of the shoe, so that the leather sole of the shoe projects beyond the plate at all points. By this arrangement, the leather itself acts as a buffer and always prevents the metal coming in contact with any of the other players.

I provide in the metal plates openings 6 through which screws 7, or any suitable fastening means may be inserted. In this instance, I prefer the screws, and by the use of these screws, the plates may be readily removed and other plates substituted. In dry weather cleats somewhat similar to those shown in Fig. 1 are used; but in wet and muddy weather longer cleats, somewhat similar to those shown in Fig. 4 are desirable, in order to prevent slipping and otherwise to cause the wearer to be sure-footed. By the use of supporting plates, a wet weather tread may be quickly and conveniently substituted for a dry weather tread.

In order to prevent the screw holes in the soles of the shoes from becoming unduly worn when other treads are substituted, I provide the openings 8 in the plate 9, shown in Fig. 4, so that they will not register with the screw holes in the soles of the shoe required for the plate shown in Fig. 1. In this way, each plate which may be used on the shoe has its screw openings located in its own particular place; and the corresponding openings in the sole of the shoe are used only for the particular plate.

The leather cleats commonly used on foot-ball shoes become soft in moist weather, and frequently by use become deformed and more or less objectionable in shape; and the moist leather, particularly when deformed, clings to mud or other moist substances, so that the tread becomes clogged, and frequently the cleats will become entirely useless as the mud forms a surface substantially flush with the treads of the cleat. I have discovered, however, that the mud does not cling materially to the metal plates; and, by the use of cleats composed of material which retains its shape

and smooth surface when wet, the mud clings to neither plate nor the cleats. Other suitable materials may be used; but I prefer for the purpose the water-proof vulcanized fiber cleats 10. I find that mud will not cling to the cleats or to the plates, when such material is used, as it retains its smooth hard surface when moist, and does not become deformed.

20 Much trouble results by the use of the ordinary leather cleats, because of the fastening means necessary to be used. These cleats are fastened by means of nails or rivets, which project through the soles of 15 the shoes. As a consequence of this method of fastening, when the leather cleats become worn somewhat on the tread thereof, the rivets are forced inwardly against the bottom of the foot, and injury frequently results thereby. By the use of my metallic 20 plates 5, the cleats 10 are riveted directly to the plates by means of rivets 11; and the sole of the shoe is sufficient protection to the foot under any ordinary conditions 25 which are likely to arise.

Also, because of the softness of the leather, and because of the necessity of forming the leather cleats out of layers of leather, it is necessary that the ordinary 30 fastening means shall extend outwardly substantially to the lower surface or tread of the leaf, and as a consequence, as the tread becomes worn, the head of the fastener becomes exposed and injury is likely to result by the projecting head of the rivet coming in contact with some other player. By the use of my cleat, however, the heads of 35 the rivets may be passed into counterbored openings 12 a very material distance from the tread of the cleat; so that there is little or no possibility of the tread being worn sufficiently to cause the rivet heads to project. And to assist in preventing wearing 40 of the tread, and to make a neater appearing cleat, and for other purposes, after the cleat has been riveted to the plate, I fill in 45 the enlarged openings 12 with some substance such as the fiber 13. The rivet-head thus becomes deeply embedded in the fiber, so that the possibility of becoming exposed 50 and thus causing injury is extremely remote. In this instance, I prepare the fiber 13 by grinding up ordinary fiber, and mixing it with shellac.

55 It is desirable for the most effective use with the above shoes to have the treads on the soles of the shoes as close to the edges of the soles as is practicable. By the use of leather cleats as ordinarily fastened to 60 the soles, it is not practicable to place the cleats close to the edge of the sole so that they extend outwardly at all beyond the foot, because they tend to turn outwardly more and more by use, and soon become 65 valueless, if not injurious. By the use of

my plates 5, which add sufficient stiffness to the sole, the cleats may be placed substantially flush with the edge of the plates. But, inasmuch as it is desirable, as hereinabove suggested, to make the plate somewhat smaller than the sole, in order to throw the tread of the cleats as far outwardly as possible, I provide cleats with the outer sides 14 thereof substantially perpendicular to the plates, as indicated in Fig. 1. I thus 75 am able to throw the tread of the cleats outwardly nearly to the edge of the sole of the shoe; and by the particular means used, am able to prevent the turning outwardly of the cleats, even in wet weather and most 80 unfavorable conditions otherwise.

It is evident that substantially all that has been said with reference to my invention and to the sole of the shoe applies 85 equally as well to the application of the invention to the heel of the shoe, it being understood that the heel of a foot-ball shoe is thin and subject to somewhat the same disadvantages as is the case with the sole.

I am aware that stiffening plates have 90 been used with shoes; but such plates are ordinarily not placed outside of the sole of the shoe and hence do not prevent sticking of mud to the tread; and they are arranged with openings through which the cleats may 95 be riveted to the leather sole; thus allowing the cleats to force through the openings more or less and cause injury to the foot; and forming otherwise an undesirable method of fastening the cleats. 100

I claim as my invention:

1. The combination of a foot-ball shoe and a tread therefor; said tread comprising a metallic plate, means for fastening said plate to said shoe, non-metallic cleats, and 105 means for fastening said cleats directly to said plate independently of the sole of said shoe.

2. The combination of a foot-ball shoe and a tread therefor, said tread comprising 110 a metallic plate, means for fastening said plate to said shoe, non-metallic cleats and means for riveting said cleats directly to said plate, the edges of said sole extending beyond the edges of said plate. 115

3. A shoe tread comprising a metallic plate and cleats fixed to said plate, said cleats being formed of water-proof vulcanized fiber.

4. A shoe tread, means for fastening said tread to the sole of a shoe; and elongated cleats fixed to said plates extending to and parallel with the outer long edges thereof, the outer sides of said cleats being substantially perpendicular to said plates. 120

5. The combination of a shoe and a tread for said shoe, said tread comprising a metallic plate; said plate extending outside continuously over approximately the entire surface of the sole of the shoe; and hori- 130

zontally elongated cleats riveted to said plate; the outer long sides of said cleats being substantially flush with the outer edges of said plate and extending substantially perpendicular therefrom, said cleats being composed of vulcanized fiber.

6. The combination of a shoe and a tread for said shoe, said tread comprising a metallic plate; said plate extending outside continuously over approximately the entire surface of the sole of the shoe; and horizontally elongated cleats riveted to said

plate; the outer long sides of said cleats being substantially flush with the outer edges of said plate and extending substantially perpendicular therefrom. 15

7. A shoe tread comprising a metallic plate and cleats riveted directly to said plate, said cleats being formed of non-metallic water-proof substances, having smooth 20 surfaces.

In testimony whereof, I hereunto set my hand.

NICOLAI B. JOHNSON.
